Winslow R. Parsons,

W. R. Parsons

UNITED STATES PATENT OFFICE.

WINSLOW R. PARSONS, OF WATERLOO, IOWA.

HEMSTITCHING ATTACHMENT FOR SEWING-MACHINES.

SPECIFICATION forming part of Letters Patent No. 311,673, dated February 3, 1885.

Application filed February 25, 1884. (No model.)

To all whom it may concern:

Be it known that I, WINSLOW R. PARSONS, a citizen of the United States, residing at Waterloo, in the State of Iowa, have invented a new and useful Improvement in Hemstitching Attachments for Sewing-Machines, of which the following is a specification.

This invention is additional to one having a like title described and claimed in my specification forming part of a previous application for patent filed July 14, 1883, Serial No. 100,840.

My present invention consists in certain novel combinations of parts and features of construction, hereinafter described and claimed, designed, primarily and as a whole, for use on under-feed sewing-machines, in combination with their ordinary or stitching presser-feet.

The special objects of this invention are, first, to form a separating-bar with a free passage above and behind it for the upper piece of cloth, and a rear pressing-surface for keeping both pieces of cloth in mesh with an under-feed by a hemstitching "block" wholly distinct from the presser-foot, so that the ordinary stitching-foot may be used as aforesaid; also, to provide for passing the loose stitches freely through the "presser" or presser-support of a hemstitching attachment or hemstitching attachments of any form; also, to provide, by improved means, for making the hemstitching more or less open or "wide" by varying the effective thickness of the separating-bar and correspondingly adjusting the presser of said hemstitching-block to preserve said free passage above the separating-bar by like means; and, finally, to facilitate making said block by constructing it in two parts, as hereinafter specified.

40 A sheet of drawings accompanies this specification as part thereof.

Figure 1 of these drawings is a perspective view of a hemstitching attachment for under-feed sewing-machines illustrating this invention. Fig. 2 is an elevation of the same in position on a sewing machine. Fig. 3 represents a sectional elevation of the same parts, illustrating the hemstitching operation. Fig. 4 represents back and edge views of the hemstitching-block shown in Figs. 1, 2, and 3. Figs. 4^x and 4^y represent end views of sets of interchangeable top pieces for separating-bar

and presser, respectively. Fig. 5 represents back and end views of a one-part block.

Like letters of reference indicate corresponding parts and their nearest analogues in the several figures.

N represents the ordinary needle-bar and needle, P the ordinary presser-bar and its stitching-foot, and F the feed-bar, of an ordinary sewing-machine.

C C represent the level of the cloth-plate, and T, Fig. 3, represents an ordinary throat-plate. These features may be those of any under-feed sewing-machine.

To keep two pieces of cloth, a b, apart during the stitch-forming period in the best way known to me, so as to cause the sewing mechanism and its threads t t² to produce the long stitches for "hemstitching," as illustrated by Fig. 3, I support a separating-bar horizontally across the path of the needle by means of a "spring-arm," A, for example, attached rigidly to and projecting from a substitute "shuttle-race slide," S, and in like manner connected with said separating-bar, so as to preclude any turning or torsional displacement of the latter by the feed. Said separating-bar may be a distinct part, B_s, of a two-part hemstitching-block, as illustrated by Figs. 1 to 4, 8c inclusive, or a portion, s, of a one-part block, B, Fig. 5. In either case the main and peculiar functions of the separating-bar and its supports are precisely alike, and in each case it is constructed with a needle hole or "slot," x, extending through its rear edge from the path or foremost reach of the needle. By uniting with said separating-bar B_s or s a presser or presser-support, B_p or p, in rear thereof, parallel therewith, and of greater vertical depth or thickness so as to project above it, with a passage-way, w, between the two, and a passage-way, v, formed in part by the sole of the ordinary presser-foot during the hemstitching operation above said separating-bar, provision is made for the free passage of the upper cloth, a, to and beneath the pressing-surface, so that both pieces shall be fed together and uniformly without the aid of a special presser foot.

To provide for the free escape of the loose stitches beneath the presser or presser-support, however the latter may be formed, I have found that it is of great advantage to

provide a groove, *u*, in the sole of the same, in line with the stitch-escape slot *x* of the separating-bar, as best shown in Figs. 4 and 5. Without this provision the stitches would sometimes catch at the front edge of the presser.

For rendering the hemstitching more or less open or wide, I provide the separating-bar, *Bs*, for example, with interchangeable top pieces, *ts*, of different thicknesses. Three are shown detached in Fig. 4° by way of illustration. More or less than three may be used. Each of these top pieces *ts* contains centrally a part of the stitch-escape slot *x*, and the bar *Bs* is constructed with an undercut groove in its top, to which they are all fitted, and in which one of a suitable thickness is held during the stitching operation, as shown in Figs. 1 and 3, its part of the slot *x* aligning perfectly with that in the bar proper. Interchangeable top pieces *tp*, Figs. 1, 2, 4°, attached in like manner to the presser *Bp*, provide for adjusting its effective thickness to that of the separating-bar, as provided with its respective top pieces *ts*. The presser top pieces *tp* obviously require no slotting. Inserted from the front in undercut stop-grooves in the line of feed, as shown, and arrested in proper position by a slight taper, as indicated, or by shoulders or offsets in customary manner, said interchangeable top pieces are readily inserted and withdrawn by the right hand of the operator without removing the attachment from the machine, and their accidental displacement in use is effectively prevented, the stop-grooves rendering them immovable save in a direction diametrically opposed to that of the feed.

The hemstitching-blocks above described for use on under-feed machines, whether constructed in one or two parts and with or without said interchangeable top pieces, are adapted for support by one and the same spring-arm *A*, as above described, by making the support end *r* of the separating-bar *Bs* or *s* relatively thick, or of the same thickness as the presser or presser-support at the support end of the latter, forming a level surface, to which the spring-arm is suitably riveted, as shown.

Manufacture is materially facilitated by making the separating-bar *Bs* and presser *Bp* as distinct parts, and uniting them to form a hemstitching-block by means of the spring-arm *A*, as illustrated by Figs. 1 to 4, inclusive. The passage-way *w* between the separating-bar and the presser may be either inclined in the direction of the feed, as shown in Figs. 1 to 4, inclusive, or have vertical walls, as represented in Fig. 5, or walls of any other approved form.

I do not claim herein, broadly, the combination on an under-feed sewing-machine, substantially as hereinbefore specified, of a separating block or bar projecting in front of and a short distance behind the path of the needle to keep two pieces of cloth apart during the stitch-forming period, an ordinary feed-dog, and a pressing-surface above said feed-dog

behind said block or bar, with a clear space immediately above said block or bar for the free passage of the upper piece of cloth over it, and a clear space or passage immediately behind said block or bar for the descent of said upper piece of cloth to and beneath said pressing-surface, for the purposes set forth. This is claimed in my previous specification aforesaid, and is hereby disclaimed in favor of my said application for patent filed July 14, 1883.

I claim as my invention and desire to protect under the present specification—

1. A hemstitching attachment adapted to be secured to the bed-plate of a sewing-machine, and having two arms—viz., a separating-bar and a presser—united at one end and separated at the other by a slot or space, the free end of the rear arm being thicker than the corresponding end of the front arm, and the latter having a needle-notch in its rear edge, as set forth.

2. In combination with the sewing mechanism and ordinary stitching presser-foot of an under-feed sewing-machine, a hemstitching block supported beneath and separate from said presser-foot, and constructed with a separating-bar and a presser of great vertical depth behind and parallel with said bar, free passage-ways for the upper cloth being formed between said bar and the presser-foot and between said bar and said presser, substantially as herein specified, for the purposes set forth.

3. In combination with the sewing mechanism of a sewing-machine, a hemstitching attachment or attachments comprising a separating-bar projecting in front of and a short distance behind the path of the needle, and provided with a rearwardly-opening stitch-escape slot, and a presser or presser-support behind said separating-bar, with a stitch-escape groove in its sole in line with said slot, substantially as herein specified, for the purposes set forth.

4. In combination with the sewing mechanism and ordinary presser-foot of an under-feed sewing-machine, a hemstitching attachment comprising a separating-bar provided with interchangeable top pieces of different thicknesses held in undercut stop-grooves in the line of feed, and a presser or presser-support provided correspondingly with interchangeable top pieces, as herein specified, for the purposes set forth.

5. The improved hemstitching attachment for under-feed sewing-machines, composed of a shuttle-race slide, *S*, a spring-arm, *A*, the separating-bar *Bs*, with its slot *x* and support end *r*, and the presser *Bp* as a distinct part, said bar and presser being separately attached to said spring-arm, so as to be supported thereby in the manner set forth.

Correction in Letters Patent No. 311,673.

It is hereby certified that in Letters Patent No. 311,673, granted February 3, 1885, upon the application of Winslow R. Parsons, of Waterloo, Iowa, for an improvement in "Hemstitching-Attachments for Sewing-Machines," an error appears in the printed specification requiring the following correction, viz: In line 95, page 2, the word "great" should read *greater*; and that the Letters Patent should be read with this correction therein to make it conform to the record of the case in the Patent Office.

Signed, countersigned, and sealed this 10th day of February, A. D. 1885.

[SEAL.]

M. L. JOSLYN,
Acting Secretary of the Interior.
